UNITED STATES PATENT OFFICE.

JEREMIAH BARNES, OF RUMMEL, PENNSYLVANIA, ASSIGNOR OF ONE-HALF
TO JOSEPH LEVANT, OF WINDBER, PENNSYLVANIA.

CAR-MOVING MECHANISM.

SPECIFICATION forming part of Letters Patent No. 745,034, dated November 24, 1903.

Application filed September 15, 1903. Serial No. 173,225. (No model.)

To all whom it may concern:

Be it known that I, JEREMIAH BARNES, a citizen of the United States of America, residing at Rummel, in the county of Somerset and State of Pennsylvania, have invented certain new and useful Improvements in Car-Moving Mechanism, of which the following is a specification, reference being had therein to the accompanying drawings.

10 This invention relates to certain new and useful improvements in car-moving apparatus; and the invention is particularly designed for the moving of cars a desired or predetermined distance for the purpose of materially facilitating the work of loading cars and at the same time permitting the load to be deposited in the car in the desired position or positions.

As practiced by me the invention is particularly designed for use in connection with the loading of coal into the cars for shipment. While designed primarily for this purpose, it will of course be evident that the invention is equally applicable to be used in connection 25 with the loading of any material into the cars where such material is deposited in the cars by the aid of a tipple and chute, as is the general practice in the loading of coal into cars for shipment.

30 Heretofore and before my invention it has been the general practice in order to move the cars up, whereby to cause the coal to be deposited at different points in the car to prevent handling of the coal by hand, to loosen the brakes of the car and push the latter or allow it to drift a desired distance and then tighten the brakes and hold the car while a quantity of coal is being deposited therein, this operation being repeated until such time 35 as the car is filled. It is the practice at many of the mines to arrange a side track adjacent the tipple at an incline, whereby to permit the ready drifting of the cars when the brakes are loosened. Many objections are to be 40 found to this system, chief among which is that it is not always possible, and, in fact, frequently impossible, to stop the car at the desired point, owing to the slippery condition of the rails or other conditions which prevent 45 the checking of the car. In event of the car drifting past the desired point considerable

labor is required to push the car back to the desired point, especially if the side track is arranged at an incline, as above stated. It is seldom that an engine is at hand to handle 55 the cars while being loaded, and consequently the return of the car to the desired point is exceedingly difficult.

It is the object of my invention to overcome all these difficulties and provide means where- 60 by one man may readily control the car, so as to permit the same to be moved up as desired to receive the material being placed in the car in order that it may be evenly filled, and to provide means whereby in event of 65 the car drifting past any desired point it may be returned to the desired point with very little labor or trouble.

In describing the invention in detail reference is had to the accompanying drawings, 70 forming a part of this specification, and wherein like numerals of reference indicate like parts throughout the several views, in which—

Figure 1 is a diagrammatical view of the 75 device as applied to the coal-tipple, showing a car in side elevation. Fig. 2 is a top plan view of the same. Fig. 3 is a top plan view of the device detached. Fig. 4 is a partial longitudinal section and side view thereof. 80 Fig. 5 is a sectional view through one of the drum-shafts, showing a part of one of the levers in side elevation. Fig. 6 is a detail side elevation of the dog-disengaging cam for one of the ratchets, showing the dog in cross-sec- 85 tion and a part of the support in side elevation.

In the present illustration of my invention I have shown the same as used in connection with loading of coal at a coal-tipple, and in the construction of these tipples it is usual 90 to employ the lower beam or beams 1 and the upper or intermediate beam or beams 2, on which latter the device is rigidly secured. As is well known, the side track is laid directly in front of the tipple 3 and the chute 95 (not shown) leads from the mine-track, whereby the coal is discharged into the chute and from thence delivered to the car.

To use my device in connection with a car 4, I attach the ropes or cables to eyes 5, which 100 are now ordinarily provided on all cars of this kind, since it is frequently desirable to

attach cables to the cars for various purposes. The device comprises a substantially rectangular frame 6, which is secured in any desired manner to the beams 2 of the coal-
5 tipple and has journaled in the side rails thereof, near one end, a shaft 7, on which is mounted a drum 8 and an operating-wheel 9, one end of this shaft being extended beyond the said rail and has mounted thereon a band-
10 wheel 10 to receive the brake-band 11, having its one end fastened to the pin or stud 12 on the side rail and its other end connected to the lower end of the brake-lever 14, pivoted to the side of the frame and having
15 a spring-pressed locking-rod 15 to engage with the segment-rack 16, carried by said frame, as in the usual construction of levers of this type. Also journaled in the side rails of the frame, and approximately central
20 thereof, is a shaft 17, on which is mounted a drum 18, carrying ratchets 19 20 on its respective ends. The ratchet 19 is engaged by a pawl or dog 21, pivoted to the operating-lever 22, which latter is loosely mounted on
25 a shaft 17, and said pawl or dog being held normally in engagement with the ratchet 19 by a spring 23 and held out of engagement by means of a cam 24, pivoted to the lever 22 and provided with a suitable handle 25 for
30 operating the cam to throw the engaging end of the pawl or dog 21 upwardly out of engagement with the ratchet 19, as will be apparent by detail view, Fig. 5. The drum 18 is loosely mounted on shaft 17 and has connected to its one end one member of the clutch 26, the other member of said clutch being connected to the side of the pinion 27, carried by the drum 28, that is keyed on the shaft 17. This shaft 17 extends through one
35 of the side rails and has mounted on said extending end a band-wheel 29, adapted to be engaged by the brake-band 30, that has its one end attached to the pin or stud 31, carried by the side rail, and its other end attached to the lower end of the brake-lever 32, pivoted to the frame and having a spring locking-lever for engagement with the segment-rack 33, the said spring locking-lever being of the same form as shown for the
40 spring-lever 14 and which is a construction well known in the arts.

The clutch 26 is engaged whereby to shift the drum 18 and engage or disengage the clutch members by the engagement of the
45 yoke end 34 with the movable clutch member carried by the drum 18, the said yoke end being carried by a substantially L-shaped lever 35, pivoted on the arm or support 36, carried by the frame. Pivotedly connected to
50 the outer end of the lever 35 is a connecting-lever 37, having its other end pivotally attached to the operating-lever 38, which is provided with a spring-pressed locking-rod adapted to engage with the segment-rack 39,
55 carried by the frame.

Journaled in the side bars of the frame, just back of the shaft 17, is a shaft 40, hav-

ing a portion 41 square in cross-section, on which is slidably mounted a pinion 42, having an integral collar 43, with which the yoke end of the shifting lever 44 is engaged, the said lever being pivotally supported on cross-bar 45 of the frame. This shaft 40 carries a ratchet 46, which is keyed on the shaft and is straddled by the bifurcated end 47 of the operating-lever 48, loosely mounted on the shaft, the said bifurcated end of the lever 48 carrying a pivoted dog or pawl 49, held in engagement with the ratchet by means of a suitable spring 50. Near the opposite end of the shaft 40 there is keyed thereon a ratchet 51, having an operating-lever 52 straddling the ratchet 51 and carrying a dog or pawl 53, held in engagement with the ratchet by the spring 54 in the same manner as above described for the lever 48. Also keyed on the shaft 40, adjacent the ratchet 51, is a ratchet or gear 55, which is engaged by a spring-pressed dog or pawl 56, pivotally supported from the side rail of the frame. This ratchet or gear 55 and pawl or dog 56 prevent backward movement of the shaft 40 when actuated by levers 48 52 being operated so as to cause their pawls to engage ratchets 46 51.

For normally holding the slidable member of the clutch 26 in engagement with the member carried by the ratchet 27 I provide a spring 57 on the shaft 17, between the one side rail of the frame and lever 22, and for elevating the dog 58 out of engagement with the ratchet 20 when the members of the clutch 26 are disengaged I provide a cam-finger 59, which is carried by the supporting-arm 36. The dog 58, which engages ratchet 20, is pivoted to the L-shaped arm 35. For the purpose of preventing the band-wheels 10 29 from becoming slippery, due to inclement weather or other causes, I provide a sanding device for these wheels comprising a hopper 60, supported by standards 61, attached to the frame of the machine. This hopper is provided in its bottom with two outlet-ports controlled by the valves 62 63, pivoted to the bottom, and which are operated by rods 64 65, extending through the side wall of the hopper and pivoted to said valves and supported near their outer ends by a standard 66, attached to the cross-bar 45 of the frame. Pipes 67 68 lead from the outlets in the hopper-bottom to the wheels 10 29, respectively.

In describing the operation attention is directed to Figs. 1, 2, 3. In the latter view all parts are shown in their normal position, the pinion 42 being shifted so as to be disengaged from gear 27 and the movable member of clutch 26 being engaged with the member carried by said gear 27. The rope or cable 69, attached to drum 18, is passed over a pulley 70, supported at one end of the frame, and then carried over a pulley 71, suitably arranged in the tipple, (see Figs. 1 and 2,) and connected to one of the eyes 5 at the rear end

of the car 4. The rope or cable 72, attached to drum 28, is passed down over a pulley 73, carried by two beams or sills 1, and hooked into one of the eyes 5 at the forward end of the car. The rope or cable 74, attached to the drum 8, is carried over pulley 75, arranged in a suitable manner in the tipple at the beams or sills 1, the hook in the end of said rope being engaged in an eye 76, arranged in the tipple at a suitable point.

Now if it is desired to permit the car to move forward, assuming one end to have been filled, the operator by actuating lever 32 loosens brake-band 30 off brake-wheel, and where the car is on an inclined track and the brakes of said car are off or loosened the car will drift or move forward, unwinding rope or cable 72 from its drum, until such time as the car has moved forward the desired distance, when the operator by tightening brake-band 30 on brake-wheel secures the cable and stops the car. At the same time while shaft 17 is revolving rope or cable 69 is being wound on its drum 18, due to the drums being at this time connected together by the clutch 26. This step is continued until the car has been loaded unless at any of the operations the car is moved a greater distance than desired, in which event the operator actuates lever 44 so as to shift pinion 42 into engagement with gear 27. Lever 38 is then actuated so as to disengage the clutch members, accomplished through the medium of levers 37 35, bringing pawl 58 into engagement with cam-finger 59, thus lifting the said pawl out of engagement with its ratchet 20. This disengagement of the dog or pawl 58, it will be observed, is automatic with the disengaging of the clutch members, and after these clutch members have been thus disengaged the operator by actuating cam 24 lifts pawl or dog 21 out of engagement with ratchet 19. The brake-band must then be released, and then by operating either lever 48 or 52, or both, reverse movement is imparted to the shaft 17, whereby to cause cable 72, attached to the front end of the car, to pull backward on said car, so as to return it the desired distance, where it is held by the tightening of brake-band 30 on brake-wheel 29. When this is done, the operator actuates lever 44 again to shift pinion 42 out of engagement with gear 27, actuates lever 38 to again engage the members of the clutch 26, which actuation allows pawl or dog 58 to again engage ratchet 20, and operator then turns cam 24, so as to permit dog or pawl 21 to again be drawn by its spring 23 into engagement with its ratchet 19. After the car has been filled ropes or cables 69 and 72 are disconnected from the car that has been filled and attached or connected to the succeeding car, and rope or cable 74 is disconnected from eye 76, (which is merely a support,) and the hook in said rope or cable is attached to one of the eyes 5 of the car and said rope thus used for permitting the car to be passed slowly down to the desired position

on the track beyond the tipple. In practice it is oftentimes customary to have the track at an incline for some slight distance beyond the tipple, and this cable 74 may therefore be used for attachment to the cars until they reach the level track at the end of the incline, where when the brakes on the car have been released for permitting the car to move forward and the car fails to drift the operator by actuating lever 22 causes pawl 21 to actuate ratchet 19 and shaft 17, and thus exert a pull on cable 69, so as to cause the car to be moved forward.

Stops 77 may be provided on the frame for holding the lever 44 in its different positions, if desired or found necessary.

The hand-wheel 9 on the shaft 7 forms a means for rewinding the rope or cable 74 onto its drum 8 after the loaded car has reached the point at which it is to be left standing and the said rope or cable 74 has been detached therefrom. The movement of the car down the incline to the point where it is to be left standing is controlled by means of the brake-band 11, brake or band wheel 10, and lever 14. The provision of the sanding device enables me to keep the band-brakes in condition for proper working at all times, irrespective of the condition of the weather.

While I have herein shown and described my invention in detail as it is practiced by me, yet it will be evident that in constructing the device to conform to various tipples various changes may be made in the details of construction without departing from the general spirit of the invention.

Having fully described my invention, what I claim as new, and desire to secure by Letters Patent, is—

1. In a device of the type described, the combination of a frame suitably mounted, a shaft journaled in said frame with two drums mounted thereon, one of said drums being keyed to the shaft and the other loosely mounted thereon, means for connecting the drums to cause the same to rotate in unison, separate cables attached to said drums and adapted for connection to a car, and a brake for said shaft.

2. In a device of the type described, the combination with a frame, of a shaft journaled in said frame, a drum fixed on said shaft with a cable connected thereto and adapted for connection to a car, a second drum loosely mounted on said shaft with a cable connected thereto and adapted for connection to a car, and means whereby said drums are rotated independently or in unison.

3. In a device of the type described, an operating-shaft suitably mounted, a drum fixed on the shaft to revolve therewith, a cable connected to said drum and adapted for connection to a car, a second drum loosely mounted on said shaft, a cable having its one end connected to said second drum and adapted to have its other end connected to a car, a clutch for effecting rotation of the drums in unison,

and means for actuating the said second drum to rotate same independently of the drum fixed on the shaft.

4. In a device of the type described, an operating-shaft, a drum fixed on said shaft to revolve therewith, a cable having its one end connected to the drum and its other end adapted for connection to a car, a second drum loosely mounted on said shaft, means for causing rotation of the drums in unison, a cable having its one end connected to the second drum and its other end adapted for connection with a car, and means for operating said second drum to rotate the same independently of the first-named drum.

5. In a car-mover, a rotatable shaft suitably journaled, a drum fixed on said shaft, a gear connected to said drum and provided with a clutch member, a second drum loosely mounted on said shaft and provided with a ratchet at each end, cables having their one end attached to said drums and their other ends adapted for connection to a car, a second shaft suitably journaled and having a pinion slidably mounted thereon, means for engaging and disengaging said pinion and the gear on the first-mentioned drum, and means for rotating the second shaft to rotate the first-mentioned shaft and drum independently of the second-mentioned drum.

6. In a car-mover, a suitably-mounted frame, a shaft 7 journaled therein, a drum mounted on said shaft, a brake for controlling said shaft, a sanding device for said brake, a cable having its one end connected to said drum and its other end adapted for connection to a car, and means connected to said shaft for rewinding the cable onto the drum.

7. In a car-mover, a suitably-journaled shaft 17, a drum fixed on said shaft to revolve therewith, a second drum loosely mounted on the shaft, means for actuating said loosely-mounted drum independently of the fixed drum, separate means for effecting rotation of the drums in unison, a brake for controlling said shaft, and a sanding device for said brake.

8. In a car-mover, the combination of a drum with a cable having its one end attached thereto and its other end adapted for connection to a car, a second drum with a cable having its one end attached thereto and its other end adapted for connection with the opposite end of a car, means for controlling the rotation of the shaft and drum, and means for effecting rotation of said drums in unison and independently of each other.

9. In a car-mover, the combination of a drum with a cable having its one end attached to said drum and its other end adapted for connection with one end of a car, a second

drum with a cable having its one end connected to the drum and its other end adapted for connection with the opposite end of said car, and means for winding one cable onto its drum while the other cable is being unwound from its drum.

10. In a car-mover, a suitably-mounted drum, a cable having its one end connected to said drum and its other end adapted for connection to a car, a second drum, a cable having its one end attached to said second drum and its other end adapted for connection to said car, clutch mechanism for effecting rotation of said drums in unison, and means whereby the rotation of each drum is effected and controlled independently of the other drum.

11. In a car-mover, a suitably-mounted drum, a cable connected to said drum and adapted for connection to a car, a second drum, rotatable independently and in unison with the first-mentioned drum, and a brake for controlling the rotation of the first-mentioned drum.

12. In a car-mover, a suitably-mounted drum, a cable having its one end connected to the drum and its other end adapted for connection to a car, a brake for controlling the movement of the drum to regulate the movement of the car, and a sanding device for said brake.

13. In a car-mover, a suitably-mounted drum, a cable connected to said drum and adapted for connection to a car, in combination with a drum 8 having a cable connected thereto with its one end adapted for connection to said car, and means for controlling the movement of said drums.

14. In a car-mover, a suitably-mounted drum, a cable having its one end connected to said drum and its other end adapted for connection to a car, a second drum with a cable connected at its one end to said drum and its other end adapted to be connected to the car, means for revolving said drums independently and in unison, and a drum 8 with a cable connected thereto and adapted to have its one end connected to the car, substantially as described.

15. In a car-mover, a frame having drums mounted therein with cables connected to said drums and adapted for connection to a car, and means for operating said drums to move the car in opposite directions.

In testimony whereof I affix my signature in the presence of two witnesses.

JEREMIAH BARNES.
